GAS RANGE

Benjamin E. Meacham and William H. Frick,
Cleveland, Ohio, assignors to American Stove
Company, St. Louis, Mo., a corporation of New
Jersey

Application October 23, 1936, Serial No. 107,286

6 Claims. (Cl. 126—39)

The present invention relates to improvements in gas ranges and pertains more particularly and specifically to a solid or closed top gas ranges such as are commonly referred to in the trade as heavy duty ranges and are used primarily by 5 hotels, restaurants, hospitals or similar institutions where continuous and large volume cooking ordinarily takes place.

One of the primary objects of the present invention is the provision of a closed or solid top cooking range the cooking top of which can be uniformly heated throughout its entire area.

Another and further object of the present invention is the provision of a solid or closed top cooking range constructed in a manner whereby, if desired, the cooking top can be utilized for fast, medium and slow cooking due to an arrangement which permits different areas of the cooking top to be heated at different temperatures. 20 Each section however of the cooking top has a uniform temperature throughout its area so that uniform cooking can be obtained on any portion of the area of a cooking top section.

Another and still further object of the invention is the provision of a closed or solid top cooking range having a novel or improved combustion chamber construction which includes a novel and improved arrangement of burners and baffles within the combustion chamber.

A still further object of the invention is the provision of a new and improved construction of top plate for a solid or closed top type of cooking range.

A still further object of the invention is the provision of a novel and improved arrangement for delivery of secondary air to the Bunsen burners of a solid or closed top type of cooking range.

Numerous other objects and improved constructional features of the present invention will appear in more detail from the following description when read in the light of the accompanying drawings.

In the drawings:

Fig. 1 is a view in front elevation of the present improved range.

Fig. 2 is a fragmentary end view of the range in vertical section.

Fig. 3 is a top plan view of the cooking top of the range, a portion of the figure being broken away and shown in horizontal section.

Fig. 4 is a vertical sectional view through the range, the view being taken on the line 4—4 of 55 Fig. 3.

Fig. 5 is a vertical sectional view taken at right angles to Fig. 4.

Fig. 6 is an enlarged fragmentary vertical sectional view taken on the line 6—6 of Fig. 3.

Fig. 7 is an enlarged fragmentary vertical sectional view showing a slight modification of the manner of feeding secondary air to the burners.

Having reference now to the drawings, 1 indicates the front frame of a range which is substantially rectangular in configuration. Centrally arranged within the range frame and behind a door 2 is an oven A. A sliding drawer 3, for the storage of utensils or the like, is positioned beneath the oven and at each side of the oven and drawer and behind suitable panels 4 10 and 5 are side compartments B. The oven and the side compartments terminate short of the top of the range frame and upon them and behind a suitable front panel 6 are arranged a plurality of combustion chambers C, D, and E which are 15 closed at their upper ends by suitable cooking top plates F, G and H respectively which are all supported in the same horizontal plane to provide a smooth cooking top. These top plates extend entirely throughout the width of the range but stop short of the front and rear of the range. At its front edge the range has a top front frame member K while at its rear the range has a rear top frame member L. The upper surfaces of the frame members K and L are 20 in horizontal alignment with the cooking top plates so that the entire upper surface of the range is smooth and flat to present an even surface over which utensils may be readily moved 25 at will.

Adjacent the rear edge of the rear top frame member L a splash back M is provided and behind this splash back are a plurality of vertically disposed flues 7, 8, 9, and 10 all of which at their upper ends converge into a single flue 11 which has an outlet 12 above and behind the rear top edge of the splash back. A high shelf is indicated at 13 to form a storage space N well above the cooking top plates. If desired this space N could 30 be provided with a front closure to constitute a warming oven.

The oven top is designated at 14 and is supported at its rear end upon the range back wall 15, at its side edges upon the range side or end 40 walls 16 and 17 and at its front edge upon a suitable angle iron bracket 18.

A manifold chamber P is disposed beneath the range top frame member K and extends from one side of the range to the other and traverses the 45 50 55

entire widths of all of the combustion chambers C, D and E. The heretofore mentioned front panel 6 constitutes the front wall of this chamber and the rear wall of the chamber is in the form of an insulated rear plate 19 which traverses the entire width of the range in spaced parallel relationship to the front panel 6. Within this chamber is the main gas supply manifold 20 for supplying gas to the mixing bells 21 of the several burners a, b, c, d, e, and f.

One side wall of the combustion chamber C is the insulated outer end wall 22 of the range while its other side wall is a vertical partition 23 the lower end of which is supported as at 24 upon the oven top while its other end terminates short of the cooking top plates and bears an L-shaped angle iron 25. The aforementioned vertical partition plate 23 together with a similar plate 23^a arranged in spaced parallel relationship constitute the side walls of the center combustion chamber D. The combustion chamber E has as its side walls the plate 23^a and the other end wall 22^a of the range. The side walls 22 and 22^a carry on their upper ends L-shaped angle bars 26.

At its inner rear edge the top frame member K has a depending portion 27 terminating in a horizontally disposed flange 28 while the front or inner edge of the rear top frame member L has a depending portion 29 provided with a forwardly and inwardly horizontal flange 30. By reference to Figs. 4 and 5 of the drawings it will be seen that the top plates F, G and H on their under sides and at their peripheral edges are provided with downwardly extending lugs 31 which engage the angle bars 25 and 26 and the flanges 28 and 30 to support the top plates in proper operative relationship to the range and to each other.

From the construction thus far described it will be seen that the combustion chambers C, D and E are independent of one another insofar as communication is concerned and that they extend from the rear wall 19 of the manifold chamber in parallel relationship towards the rear end of the range and are of a combined width equal to the width of the range top. At their rear ends these combustion chambers are closed by a rear wall 32. The vertical division plates 23 and 23^a extend rearwardly past the rear wall of the combustion chambers to provide at the rear of the range and beneath the rear top frame member L a plurality of flue boxes R, S and T. These flue boxes communicate in turn with their respective vertical flues 7, 8 and 10 for the purpose of discharging through the outlet 12.

An outlet flue box V has communication with the oven A as at 35. This flue box communicates with the vertical flue 9 which passes upwardly centrally through the aforementioned flue 8 as clearly appears in dotted lines on Fig. 1 of the drawings.

Each of the burners a to f inclusive is similarly constructed. These burners are straight elongated tubular burners and on the opposite edges of their tops are drilled with burner orifices 36 which are disposed at an angle to the vertical so that the burners will burn divergently extending tongues of flame. Each combustion chamber is provided with two burners which in respect to one another are arranged in separated parallel relation. These burners extend from the front towards the rear of the range and each of them is disposed within a housing having an open upper end.

75 Each combustion chamber has a bottom plate

37 which is arranged above and in separated parallel relationship to the top 14 of the oven to provide beneath the combustion chamber bottoms conduits X, Y and Z. Describing the combustion chamber C which will also describe all of the other combustion chambers as they are identical in construction, it will be seen that at each side of the burner a there are upwardly extending vertically disposed baffle walls 38 and 39 the lower ends of which are supported as at 40 and 10 41 upon the combustion chamber bottom 37 while their upper ends extend well above the burner and terminate short of the under side of the cooking top plate F. Similar baffle walls 42 and 43 are provided for the burner b. These vertically disposed baffle plates extend from the rear wall 19 of the manifold housing back to the rear wall 32 of the combustion chamber and therefore in a sense divide the combustion chamber up into a plurality of channelways. One of the channelways is designated at 44 and lies between the outer end wall 22 of the range and the baffle plate 39. The second channelway 44^a lies between the baffle plates 38 and 39 and the burner a is positioned within this channelway. A second 20 channelway 45 lies between the baffle plates 38 and 43 while the burner b is in the next channelway 46 which lies between the baffle plates 42 and 43. The last channelway 47 is similar to the aforementioned channelway 44 and lies between 30 the baffle plate 42 and the vertically disposed division wall 23 which separates the combustion chamber C from the combustion chamber D.

The bottoms of the channelways 44, 45 and 47 which lie at each side of the burners are lined 35 with fire brick 48 or other suitable like material. These brick lined channelways at their rear ends communicate with the flue box R through suitable openings 49, 50 and 51 provided in the rear wall 32 of the combustion chamber.

It will be understood that all of the burners are Bunsen burners and that to obtain the proper combustion it is necessary to furnish secondary air to the burners. In the preferred form of the invention secondary air is admitted into the manifold housing P through an opening 52 provided in its front panel 6. This is the opening through which the stem 53 of the valve operating handle 54 extends. Incidentally the supply of gas to both of the burners a and b is under the control of this single valve so as to assure uniform flame at the burners and uniform heat delivery by the burners. The secondary air which enters the manifold chamber P can enter each of the channelways 44 and 46 within which the burners are positioned through the openings 55 through which the mixing bells 21 of the burners extend. Secondary air admitted at this point is supplied both above and below the burner. Secondary air can also pass from the manifold chamber P into the conduit X through openings 56 provided in the front wall of said conduit. Additional secondary air reaches the conduit X from the side chambers B through suitable openings 57 provided in their tops. All of the secondary 65 air carried by the conduit X is delivered to the under side of the burners at spaced points throughout their lengths through suitable openings 58 provided in the top wall of the conduit.

The secondary air delivered to the burners 70 from the conduit X enters the channelways 44 and 46 beneath the burners. Part of this air is delivered directly to the burner stools or to the flames themselves while a portion of it is delivered to the combustion chamber at a point above 75

the burners. This is accomplished by baffle plates 100 and 101 which are disposed at each side of each burner and extend upwardly and inwardly from the vertical baffle plates towards the burners. These baffle plates extend throughout the length of the burners and are supported in proper operative position by having leg portions 59 which abut the vertical baffle plates and having throughout their length a plurality of lugs 60 carried by the inclined portions of the baffles and engaging the upper surface of the burners at a point slightly beneath their burner orifices 38. These air baffles 100 and 101 have downwardly extending fins 61 which are in separated parallel relationship to the side of the burners and extend throughout the length of the burners.

Part of the secondary air within the channels beneath the burners will pass upwardly between the fins and the burners and through the spaces 20 provided between the lugs 60 and thus directly pass the base of the flames burned at the burner orifices. Additional secondary air will pass up on the other side of the fins and into the combustion chamber above the burner through suitable openings 62 provided in spaced relationship periodically throughout the lengths of the upwardly and inwardly inclined portions of the air baffles 100 and 101.

Fig. 7 illustrates a slightly modified form of 30 the invention in that a series of openings 64 are provided in the rear wall 32, for delivering secondary air into the rear ends of those channelways within which the burners are positioned. This modification merely permits the provision of 35 an additional amount of secondary air to that which is provided in the preferred form of the invention.

Describing the cooking top plate F, it will be seen that immediately above the burners a and b 40 it is thickened as indicated at 65 and that from these thickened portions it tapers in both directions so that immediately above the side channelways 44 and 47 and the central channelway 45 the top plate is comparatively thin, as indicated 45 at 66, 67 and 69. This plate at the under side of its marginal edges is provided with downwardly extending fins 69 and 70 which extend throughout the length of the plate and a fin 71 extends throughout the length of its center portion and 50 extends well down into the central channelway 45 to terminate at a point below the upper ends of the channelway walls 38 and 43. In addition to the longitudinally extending fins 69, 70 and 71 the under side of the cooking top has a longitudinally 55 extending fin 72 positioned centrally above the burner a and a longitudinally extending fin 73 above the burner b. These fins are comparatively shallow and do not extend downwardly into the combustion chamber very far as their 60 lower edges terminate slightly above the upper edges of the vertical baffles at the sides of each of the burners.

The under side of the cooking top plates are also provided with transversely extending fins 65 which are arranged in separated spaced parallel relationship and are designated at 74. These fins intersect the longitudinal fins 72 and 73 and are of a length equal to the distance between the vertical baffles at the sides of the burners. These 70 fins are comparatively shallow and do not extend very far downwardly into the combustion chamber with the exception of the first fin 75 at the forward edge of the plate and the rear fin 76 at the rear edge of the plate. The fins 75 and 76 extend completely across the width of the com-

bustion chamber and are of a depth similar to the depth of the longitudinally extending fins 69, 70 and 71 and it is therefore necessary to notch out the vertical baffle plates 38, 39, 42 and 43 as indicated at 77 for the front fin and 78 for the rear fin. The rear fin is cut out as at 79 so as not to form an obstruction to the passage of the products of combustion outwardly through the opening 50 into the flue box for discharge.

From the foregoing description it will be seen 10 that in respect to each combustion chamber that the cooking top immediately above the burners and at the point where the burner flame will impinge, is thickened and that it then tapers away with the result that the taper assists in directing 15 the flames and the hot products of combustion under and against the remaining portions of the cooking top and particularly those portions of the cooking top which are thinner and more remote to the burners. By thickening the tops at 20 the point of flame impingement over-heating of the tops in a concentrated area above the burners is prevented while the inclination of the under side of the tops assists in preventing local over-heating by causing heat and flames to move 25 rapidly to those portions of the cooking top lying at each side of the burner. This rapid movement of the heat and flames away from the burners is also of material importance in obviating any possibility of the flames at the burners being 30 smothered.

The fins 72 and 73 immediately above the burners serve a double function in that they are strengthening ribs to prevent the cooking tops from warping and in that they act as division 35 plates for causing the flames of each burner to be divided and the heat from them directed to that portion of the cooking top lying to each side of the burner.

The draft in each combustion chamber is of 40 course from the front towards the rear in that each of the combustion chambers discharge at their rear ends into a flue box which is in turn connected to the main range outlet flue. The cross ribs or fins 74 in addition to strengthening 45 the cooking tops act as heat absorption fins and most important of all tend to definitely direct the hot products of combustion into the channelways at each side of each of the burners so that these hot gases will travel rearwardly under the thinner 50 portions of the cooking top plates to discharge. The thinner portions of the cooking top plates are the portions which are remote to the burners and by causing the major portion of the hot gases to travel beneath them it has been found that this 55 fact taken together with the thickened portions of the cooking top plates immediately above the burners an even temperature can be obtained throughout the entire area of the cooking plate above each combustion chamber. This is a decided improvement and advantage and something which it has not been possible to obtain in solid top cooking ranges as heretofore known to us.

The longitudinally extending ribs or fins 71 which are centrally positioned in each combustion chamber in addition to serving as a strengthening 65 means for the cooking top serve as heat absorption means for conducting heat to a thinner portion of the cooking top plates which are remote to the burners and function in another 70 important manner by serving as a division plate between the two burners of each combustion chamber to assure that the flames which lick or reach outwardly from these burners remain separate and do not intermingle until the burning 75

gases are well downwardly within the channelways 45 which lie between the adjacent vertical baffles 38 and 43.

The vertical baffle plates 38, 39, 42 and 43 provided in each combustion chamber are important in that first they act as guides for directing the impingement of the burner flames against the thickened portions of the cooking top plates and in directing upwardly against this portion of the 10 cooking top plates the heat generated at the burners. They also perform the important function of preventing burning gases from possibly reaching or striking back at the burners themselves so as to prevent any possibility of the 15 flames being smothered. In other words, these baffle plates taken together with the described means of providing secondary air assure burner efficiency.

It will be recognized that each pair of burner 20 arms in each combustion chamber can be operated independently. A single gas valve controls the supply of gas to the burners in each individual combustion chamber which assures a uniform flame and a uniform heat in each burner arm. 25 When all of the gas valves are set in a similar manner a uniform temperature will be obtained throughout the entire area of the range top. By varying the settings of the gas valves different 30 cooking temperatures can be obtained on the individual plates F, G and H, but on each plate the temperature will be uniform throughout its entire area. It is due largely to the fact that the individual combustion chambers can be individually operated that individual outlets for 35 them are provided. Individual flues will provide better operation but are not necessarily essential and a single flue for all of the combustion chambers could be substituted were it desired.

From the foregoing it will be understood that 40 a greatly improved range is provided in that on a single range three different cooking temperatures can be obtained if desired or a positive uniform temperature obtained throughout the entire area of the cooking top. It is essential to 45 obtain the best cooking results that the cooking top does not have hot spots, and in the present range hot spots are obviated and a uniform temperature is obtained from edge to edge of the range cooking top. In actual practice it has been 50 found that an even heat or a uniform heat is obtained everywhere on the top plate and that it has been possible to acquire a top plate temperature as high as 1050° F. with that temperature evenly and uniformly distributed on the cooking 55 surface.

We claim:

1. In a range, a solid cooking top, a plurality of independent combustion chambers therebeneath, each combustion chamber being provided with a plurality of vertically extending baffle plates disposed in parallelism and dividing said combustion chamber into a plurality of parallel channelways, a Bunsen burner composed of a pair of elongated burner arms, a flue at the rear of the 60 range, communication only between said flue and alternate channelways, the other channelways constituting burner housings for said elongated burners, a secondary air conduit beneath each combustion chamber, means to admit air to said 65 conduits, and means to admit air from said conduits into said burner housing channelways at a point beneath the burners.

2. In a range, a solid cooking top, a plurality of combustion chambers therebeneath, each combustion chamber being provided with a plurality

of baffle plates disposed in parallelism and extending vertically from the bottom of said combustion chamber and dividing said combustion chamber into a plurality of parallel channelways, an outlet flue at the rear of the range, outlet openings in the rear of said combustion chamber providing communication between the outlet flue and the rear ends of alternate channelways only in each combustion chamber, an elongated burner arm positioned in each of the other combustion chamber channelways, and communication between the channelways carrying the burners and the channelways at either side thereof. 10

3. In a range, a solid cooking top, a combustion chamber therebeneath, an elongated burner 15 extending substantially entirely across said combustion chamber, a housing for said burner having an open upper end, a channelway at each side of said burner housing, a flue outlet having communication only with the rear end of each of said 20 channelways, a secondary air conduit for admitting secondary air into said burner housing at a point beneath the burner, baffles in said burner housing for directing a portion of the secondary air directly to the flames burned at said burner 25 and directing a portion of the air around said burner and into said burner housing at a point above the burner and said burner housing adapted to direct the burner flames against the under side of the cooking top and to prevent the 30 flames from striking back at the burner.

4. In a range, a burner chamber having side, front and rear and bottom walls and provided with a solid cooking top, a plurality of baffle plates disposed in parallel relationship and extending from the bottom wall of said chamber vertically and terminating short of the under side of said solid cooking top to form a plurality of parallel channelways, a flue box beyond the rear wall of said chamber, outlet openings in said 40 chamber rear wall into alternate channelways, an elongated burner arm positioned in each of the other channelways which have no communicating opening with the flue box, communication between those channelways carrying the burners 45 and the other channelways over the tops of said baffle plates, a secondary air conduit extending completely under the entire chamber bottom and provided with openings admitting secondary air into those channelways carrying burners at a 50 point below said burners, baffles extending from each of said burners to the vertical baffles forming the walls of the burner channelways, each of said baffles permitting secondary air to pass directly to the burner ports of said burners and 55 directing a portion of the secondary air past the burners and into channelways at a point above the burner orifices, and means at the under side of the cooking top for directing the hot products of combustion generated by the burners into the 60 channelways lying at each side thereof.

5. In a range, a main combustion chamber having a solid cooking top and side rear front and bottom walls, a plurality of division plates extending from the bottom of said chamber to 65 the solid top thereof and dividing said chamber into a plurality of supplemental independent non-communicating combustion chambers, a pair of elongated burners within each burner chamber extending from the front towards the 70 rear thereof in separated parallel relationship, vertically extending baffle plates at each side of each of said burners extending from the bottom of the combustion chambers to a point short of the solid top thereof and from the front wall 75

of the combustion chambers to the rear walls thereof to form a housing having an open top for each burner, said vertically extending baffle plates forming a channelway at one side of and intermediate each of said burners, a flue outlet beyond the rear wall of said combustion chambers, a secondary air conduit for admitting air into each burner housing at a point beneath the burners therein, baffles in said burner housings for directing a portion of the secondary air up each side of each burner and directly to the flames burned at said burners and directing a portion of the secondary air around each side of each burner and into said burner housings at a point above said burners, said cooking top immediately above said burner housings being thickened and constructed to direct products of combustion of the burners into the channelways at either side of the burners, and communication between the channelways and the flue at the rear of the range for creating a rearwardly moving draft in the channelways to assist in moving the products of combustion from the burners into the channelways and under and against the thinner portions of the cooking top lying above the channelways.

6. In a range, a burner chamber having side, front, rear and bottom walls and provided with

a solid cooking top, a plurality of baffle plates disposed in parallel relationship and extending from the bottom wall of said chamber vertically and terminating short of the under side of said cooking top to form a plurality of parallel channelways, an outlet flue at the rear of said chamber and having communication with alternate channelways only of said chamber, an elongated burner positioned in each of the other channelways of said chamber, communication between those channelways carrying burners and the other channelways over the tops of said baffle plates, a secondary air conduit for admitting air into those channelways carrying burners at a point below said burners, baffles extending from each of said burners to the vertical baffles forming the walls of the burner channelways, each of said baffles permitting secondary air to pass directly to the burner ports of said burners and directing a portion of said air past the burners and into the channelways at a point above the burner orifices, and means at the under side of the cooking top for directing the hot products of combustion generated by the burners into the channelways lying at each side thereof. 25

BENJAMIN E. MEACHAM.
WILLIAM H. FRICK.
